ELASTIC FLUID TURBINE DIAPHRAGM SUPPORTING AND CENTERING ARRANGEMENT

Max A. Hinrichs, Millbrae, Calif., assignor to General Electric Company, a corporation of New York

Application January 25, 1940, Serial No. 315,564

4 Claims. (Cl. 253—78)

The present invention relates to elastic fluid turbine diaphragm supporting and centering arrangements. More specifically the invention relates to the kind of turbine arrangements in which both the turbine casing and the diaphragms for conducting elastic fluid to the bucket wheels are made of two halves joined together with the diaphragms supported on the casing. Still more particularly the invention relates to diaphragms for conducting the elastic fluid from an extraction or mixed pressure stage to a lower stage and in which one of the diaphragm halves forms a support for a valve body forming a valve seat in cooperative relation with a valve held in the casing. In order to attain the desired operation of such arrangements they have to meet two requirements. First, the extraction stage diaphragm has to be in concentric relation with the shaft or the rotor of the turbine to assure proper cooperation between a row of nozzles formed by the diaphragm and the buckets of the adjacent bucket wheel. Such concentric relation also assures proper operation of a packing between the diaphragm and the turbine shaft. Second, the valve seat or seats formed on the valve body must be located in a plane parallel to corresponding surfaces on the movable valve member or members on the casing.

The object of my invention is to provide an improved construction and arrangement of extraction stage diaphragm centering and supporting arrangements whereby the aforementioned requirements are met in a simple and satisfactory fashion.

For a consideration of what I believe to be novel and my invention, attention is directed to the following description and the claims appended thereto in connection with the accompanying drawing.

In the drawing, Fig. 1 illustrates a sectional view of an extraction turbine arrangement embodying my invention; Fig. 2 is a view along lines 2—2 of Fig. 1; Fig. 3 illustrates an enlarged, exploded, perspective view of a part of Fig. 2; and Fig. 4 is an enlarged sectional view of a part of Fig. 2.

The arrangement comprises a turbine casing having lower and upper halves 10 and 11 respectively with flanged portions securely joined together in a plane through the axis of rotation by means of bolts 12. A turbine rotor is disposed within the casing and includes a high pressure bucket wheel 13 and a low pressure bucket wheel 14, both secured to a shaft 15. Elastic fluid is

directed to the bucket wheels 13 and 14 by means of stationary diaphragms 16 and 17 respectively supported on the casing. The stages 16, 13 and 17, 14 are considerably axially spaced and the lower turbine casing half 10 has an opening 18 between the two stages for extracting elastic fluid from the turbine or supplying elastic fluid thereto. In case the turbine is operated as an extraction turbine, part of the elastic fluid discharged from the bucket wheel 13 is extracted through the opening 18 and the other part is conducted to the lower stage 17, 14. If elastic fluid is supplied through the opening 18 to the turbine, then this elastic fluid together with the elastic fluid discharged from the bucket wheel 13 is conducted to the bucket wheel 14. Often it is desirable to control the pressure condition ahead of the bucket wheel 14 in response to changes in flow of fluid through the opening 18. This is accomplished in the present arrangement by a poppet valve arrangement comprising a valve body 19 centered on and secured to the diaphragm 17 by means of a plurality of bolts 20 and a weld 21 and forming valve seats 22 in cooperative relation with a plurality of disk valves 23 having stems 24 guided on a cover plate 25 secured to an opening of the turbine casing. The diaphragm 17 has a lower half 26 and an upper half 27, the latter carrying the valve body 19 and forming a plurality of nozzle openings 28 arranged to receive elastic fluid from the channel formed by the body 19 and conducting the fluid to the bucket wheel 14. An outer portion of the diaphragm forms an annular projection 29 projecting into an annular groove 30 formed by the casing 10, 11. The diaphragm and the casing form a radial clearance 31 between them to permit of relative expansion. The projection 29 in the recess 30 on one side engages a shoulder formed in the recess and on the other side forms an axial clearance 32, permitting relative axial expansion between the diaphragm and the casing. The diaphragm is forced into contact with the aforementioned shoulder in said recess by the action of steam pressure during operation. A plurality of axial crush pins 33 secured to the diaphragm reduce excessive axial movement of the diaphragm during shipping and operation. The engagement between the diaphragm 17 and the shoulder formed on the casing reduces leakage of elastic fluid along the inner surface of the casing. Leakage along the shaft is reduced by means of a packing of known construction, and including a packing ring 35 having a plurality of segments held in archbound

relation and biased towards the shaft by means of flat springs 36.

Proper operation of the arrangement requires that the diaphragm 17 be concentric with the shaft 15 and that the face 37 of the valve body 19 be parallel to the face 38 of the casing engaging the cover 25. This is accomplished in accordance with my invention by an arrangement for adjustably supporting the diaphragm on and centering it in the casing. More specifically, this arrangement includes means for vertically centering the diaphragm so that its center coincides with the center of the shaft and means for slightly rotating the diaphragm into a position in which the valve seats on the face 37 of the valve body 19 are parallel to the face 38 of the casing.

In the present arrangement the diaphragm halves 26, 27 are centered on each other, that is, prevented from moving axially and laterally relative to each other by means of horizontal keys 40, 41 and a vertical key 42 respectively. The lower diaphragm half 26 is supported on the lower casing half 10 by lug arrangements 43 and 44 on opposite sides of the diaphragm. Each lug arrangement includes a lug 45 secured in a recess 46 of the casing by means of a bolt 47 and having a portion projecting into a recess 48 in the diaphragm. The recess 48 is near the upper face of the lower diaphragm half 26 and the lug 45 in the recess 48 is engaged by a screw or threaded pin 49 screwed into a vertical bore between the face of the diaphragm half 26 and the recess 48. Prior to assembly the screws 49 of the lower diaphragm half 26 are adjusted so that the center of the diaphragm coincides with the center of the casing. The lower diaphragm half is centered vertically in the lower casing by the lug arrangements 43, 44. The upper diaphragm half 27 prior to assembly is similarly centered vertically in the upper casing half 11 by means of similar, adjustable lug arrangements 50 and 51 respectively on opposite sides of the upper diaphragm half 27. Prior to assembly the lug arrangements 50, 51 support the upper diaphragm half 27 on the casing half 11 whereas subsequent to assembly of the turbine the lug arrangements 50, 51 prevent upward movement of the upper diaphragm half 27 relative to the lower diaphragm half 26. Such lug arrangements are more fully disclosed in the copending applications of Johnson and Wadden, Serial No. 315,548, and Webster, Serial No. 315,547, filed on the same date and assigned to the same assignee as the present application.

The means for circumferentially adjusting the diaphragm comprises an adjustable dowel 52 which has an enlarged lower portion 53 rigidly held in a vertical opening 54 in the bottom portion of the lower casing half 10. An upper portion 55 of the dowel 52 projects into a recess or slot 56 in the lower portion of the lower diaphragm half 26 and is provided with a cross pin or screw 57 adjustably secured to, in the present instance screwed into, the upper portion 55 of the dowel pin 52. As best shown in Fig. 4, the length of the cross pin 57 is equal to the circumferential width of the recess 56 and the diameter of the upper portion 55 of the dowel pin in the present example is somewhat smaller than the circumferential width of the recess 56. Opposite sides of the upper portion 55 through which the cross pin 57 projects are flattened to permit increased adjustment of the cross pin 57.

With such an arrangement the diaphragm may be rotated slightly by adjustment of the cross pin 57

57 or, from another viewpoint, adjustment of the cross pin 57 upon removal of the diaphragm from the casing necessitates slight rotation of the diaphragm. If upon assembly of the turbine casings it is found, for example, that the left-hand side (Fig. 2) of the face 37 is too low and the right-hand side (Fig. 2) of the face 37 is too high, the upper casing half is lifted from the lower casing half and the cross pin 57 is turned clockwise from the right-hand side so that the pin projects more to the left. This of necessity requires slight circumferential movement or rotation of the lower diaphragm half in clockwise direction. To permit of such movement and to assure proper support on the lugs 45, the screw 49 on the left-hand side is turned clockwise and the screw 49 on the right-hand side is turned counterclockwise. (All screws 49 and 57 are right-handed.) In this manner the lower diaphragm half is slightly turned and maintained concentric with the shaft though its upper face is no longer horizontal and in a plane with the joint of the casing halves 10, 11, it sufficing that the center of the lower diaphragm half coincides with the center of the shaft.

25 Horizontal adjustment of the lower diaphragm half requires similar adjustment of the upper diaphragm half. In the above example where the left-hand screw 49 has been turned clockwise and thereby the left-hand portion of the lower diaphragm half 26 moved upward it becomes necessary to turn the screw 49 on the left-hand side of the upper diaphragm half counterclockwise and the screw 49 on the right-hand side of the upper diaphragm half 27 clockwise.

30 If upon assembly of the turbine casings with the diaphragms it is found that the left-hand side of the face 37 of the valve body 19 is too high or, from another viewpoint, that the plane of the face 37 of the valve body and the plane of the face 38 of the casing converge towards the left, the adjustable cross pin 57 and the screws or pins 49 of the lug arrangements are adjusted similarly as described above except that they are then turned in the opposite direction as before.

35 Having described the method of operation of my invention, together with the apparatus which I now consider to represent the best embodiment thereof, I desire to have it understood that the apparatus shown is only illustrative and that the invention may be carried out by other means.

40 What I claim as new and desire to secure by Letters Patent of the United States is:

1. Elastic fluid turbine diaphragm centering and supporting arrangement comprising a turbine casing, an intermediate stage diaphragm disposed within and engaging a shoulder on the casing, means controlling the flow of fluid to the diaphragm comprising a valve body forming a valve seat and being secured to the diaphragm and a movable valve member guided on the casing, and means centering and supporting the diaphragm of the casing comprising adjustable means between spaced portions of the casing and the diaphragm and an adjustable pin secured to another portion of the casing and projecting into a recess in the diaphragm.

2. Elastic fluid turbine diaphragm centering and supporting arrangement comprising a casing having lower and upper halves with an opening in one of the halves for extracting fluid from or supplying fluid to an intermediate stage, a diaphragm for conducting elastic fluid from such intermediate stage to the succeeding stage, such diaphragm having two halves, means for con-

trolling the flow of fluid through the diaphragm comprising a valve body forming a valve seat secured to one of the diaphragm halves and a movable valve member in cooperative relation with the seat and supported on the casing, and means supporting and centering the diaphragm on the casing, said means comprising an adjustable lug arrangement on each side of each diaphragm half, and adjustable means for slightly rotating the diaphragm into a position in which the valve seat is parallel to the cooperating surface of the movable valve member.

3. Elastic fluid turbine diaphragm centering and supporting arrangement comprising a casing having lower and upper halves with an opening in one of the halves for extracting fluid from or supplying fluid to an intermediate stage, a diaphragm having two halves for conducting elastic fluid from the intermediate stage to the succeeding stage, a valve body forming a valve seat and being secured to one of the halves, a movable valve member in cooperative relation with the seat and supported on the casing, and

5 adjustable means supporting and centering the diaphragm on the casing, said means comprising a lug arrangement on each side of each diaphragm half, and adjustable means for slightly rotating the diaphragm into a position in which the valve seat is parallel to the cooperating surface of the movable valve member, said last named means comprising a dowel pin secured to a lower portion of the lower casing half and having an adjustable cross pin engaging a recess in the lower diaphragm half.

10 15 20 4. An article of manufacture for adjusting diaphragms in turbine casings comprising a dowel pin having a portion for attachment to such turbine casing and another portion with flattened sides for projecting into a recess of such diaphragm, and an adjustable cross pin screwed into an opening through the flattened sides of the other portion and having ends projecting laterally outward from the flattened sides of the other portion for engaging the wall of such recess.
